UNITED STATES PATENT OFFICE.

HENNING BACKSTROM, OF CHICAGO, ILLINOIS.

WINDOW-SCREEN.

1,112,590.

Specification of Letters Patent.

Patented Oct. 6, 1914.

Application filed July 25, 1912. Serial No. 711,556.

To all whom it may concern:

Be it known that I, HENNING BACKSTROM, a citizen of the United States, and a resident of the city of Chicago, county of Cook, 5 and State of Illinois, have invented certain new and useful Improvements in Window-Screens, of which the following is a specification.

My invention relates to window screens 10 and particularly to screens in which the screen fabric is removably secured to the frame.

The object of this improvement is to provide a device of the character mentioned 15 which will be simple of construction and efficient in operation.

Other objects will appear hereinafter.

The invention consists in the combinations and arrangements of parts hereinafter described and claimed.

The invention will be best understood by reference to the accompanying drawings forming a part of this specification, and in which,

25 Figure 1 is an elevation of a screen made in accordance with my invention, and showing a portion of the screen fabric and retainers removed exposing a portion of the frame, Fig. 2 is a view on line 2—2 in Fig.

30 1, Fig. 3 is a view on line 3—3 in Fig. 1, and Fig. 4 is a view, in perspective, showing a fragment of the channel guide in which the screen is mounted.

The preferred form of construction, as 35 illustrated in the drawings, comprises a frame made up of bars 5 joined together at their end portions by means of bolts or rivets 6. Such bars 5 are joined as indicated in Fig. 1 so that there is a small recess 40 in the corner to accommodate a double folding of the screen fabric.

The screen fabric 7 is stretched across the frame and its edge portions bent around the outer edges of the bars 5 and the resilient 45 retaining members 8 clamped on the fabric and bars as clearly illustrated in the draw-

ings. The resilient retainers 8 are preferably U-shaped in cross section and the leg portions of the retainers clamping the wire on the frame as described. When the screen 50 fabric has become worn or it is desired to replace it for any reason the retainers 8 may be removed and a new wire fabric stretched across the frame bars 5 and the retainers 8 again replaced in position to secure the 55 screen fabric.

A channel guide 9 is provided on each side of the screen, to the window casing 10, for mounting the screen therein. Screws or nails 11 are provided at intervals along the 60 channel guide 9 to secure the channel guides to the window casing.

While I have illustrated and described the preferred form of construction for carrying my invention into effect this is capable of variation and modification without departing from the spirit of the invention. I, therefore, do not wish to be limited to the exact details of construction set forth but desire to avail myself of such variations and 65 modifications as come within the scope of the appended claim.

Having described my invention what I claim as new and desire to secure by Letters Patent is:

A window screen comprising a frame provided with recesses at its four outer corners; screen fabric stretched over said frame and folded upon the same at the edges, the corners of said fabric being folded into said 80 recesses; and removable U-shaped channel members placed over the sides and ends of said frame to secure said fabric thereto, substantially as described.

In testimony whereof I have signed my 85 name to this specification in the presence of two subscribing witnesses.

HENNING BACKSTROM.
